Frank A. Muller, Philadelphia, Pa.

Application May 26, 1954, Serial No. 432,528

1 Claim. (Cl. 36—2.5)

The present invention relates to shoes for men, women and children and, more particularly, to a basic unit thereof to which may be attached a variety of types of uppers structures for forming a variety of styles.

A general object of the present invention is to provide such a basic unit as a one-piece molded plastic structure which can be readily and economically manufactured in mass production of a plurality of sizes to which different types of uppers may be attached in a simple manner for producing an unusually large variety of styles, allowing retailing at very low prices of shoes having many advantages over more expensively produced leather shoes, such as unusual fit assuring maximum comfort, shape-retention, water-proofness, electrical non-conductivity, long-lasting attractive finish, immunity to attack by mold and destructive bacteria insuring long service life, long wearing quality and scuff-proofness, and other desirable features hereinafter made apparent.

A more specific object of the present invention is to provide such a molded plastic basic shoe unit which may be rapidly produced by molding under heat and pressure as a finished product requiring no further finishing or work thereon other than simple procedures of attaching upper means thereto, such unit comprising as integral portions a heel, counter, shank, and forepart in the form of a tread sole portion flanked by an upstanding forepart foxing merged with the counter.

A further object of the present invention is to provide an embodiment of the footwear of the present invention which may be readily and cheaply made and which assures efficient service.

Other objects of the invention will in part be obvious and will in part appear hereinafter.

The invention accordingly comprises an article of manufacture possessing the features, properties, and the relation of elements which will be exemplified in the article hereinafter described, and the scope of the invention will be indicated in the claim.

For a fuller understanding of the nature and objects of the invention reference should be had to the following detailed description taken in connection with the accompanying drawing, in which:

Fig. 1 is a longitudinal sectional elevation of an embodiment of the plastic shoe unit of the present invention and a mold for forming it, the latter being illustrated in diagrammatic form as employed in molding the shoe unit;

Fig. 2 is an elevational perspective of the right shoe unit of the type depicted in Fig. 1, as viewed from the front;

Fig. 3 is a longitudinal sectional elevation of the shoe unit of Fig. 2, shown with a body of filler material located in the heel well and an insole mounted in the unit; and

Fig. 4 is a perspective view of the left shoe unit of the

2

type shown in Fig. 1, as viewed from the side and below, illustrating in dotted lines a typical upper which may be attached thereto for completion of a certain style of shoe.

Referring to the drawing, in which like numerals identify similar parts throughout, it will be seen that an embodiment of the present invention comprises a molded plastic basic shoe unit 10 illustrated in Fig. 1 as being molded with the use of a mold apparatus 11, which may consist of a female die 12 and a male die 13. Preferably, 10 the plastic shoe unit 10 is to be molded from a suitable synthetic polymer composition which may assure to the molded unit leather-like characteristics and, more specifically, those indicated herein. Such plastic material may be a suitable polyvinyl chloride composition, plasticized, if desired, in which may be incorporated, if wished, any suitable coloring and/or opaques material. If the selected plastic material is of the thermoplastic type, the molding apparatus will, of course, be so constructed as to apply the necessary shaping pressure and plasticizing heat, 20 and may include cooling means in accordance with the teachings of the molding art, the specific techniques of which form no part of the present invention.

The male and female dies 12 and 13 may be made of fine tool steel with the surfaces 14 and 15 defining the 25 mold cavity preferably being suitably plated, such as with chromium, preferably buffed to a smooth finish of high polish to give to the molded shoe unit 10 a highly polished and finished surface which may be similar to that of fine patent leather or high-grade kid or calf skin. Such a 30 molded shoe unit 10 may require 45 seconds to 2½ minutes to produce, depending upon the characteristics of the particular plastic composition used and the cooling factor, i. e. a period of time sufficient to assure under certain conditions solidification to permit the molded unit 35 to be stripped from the female die cavity. The molded plastic shoe unit 10, in the form illustrated in the drawing, consists of a waterproof, unitary structure of plastic material having comfort-contributing but limited flexibility and some elasticity to be fit-adaptable and self-shape-retaining without discomfort to the wearer while 40 having sufficient stiffness to give adequate support, and is of good wearing quality and substantially scuff-proof. This basic shoe unit 10 consists of a heel portion 16, a full counter portion 17, a forepart tread sole portion 18, a 45 shank portion 19, and a vamp foxing 20.

The heel portion 16 of the illustrated embodiment may include a substantially flat bottom 21 substantially D-shaped in outline; a transverse, upwardly-extending breast 22; and side walls 23, preferably of conventional shape, 50 and together defining an open top well 24, as shown.

The full counter 17 is superposed above the heel side walls 23 and is in the form of two integral shaped quarters, i. e., the inside quarter 25 and the outside quarter 26, which, as will be best seen from Fig. 2, are noticeably curved inwardly or concaved so as to attain a desired snug fit to the sides of a person's heel, which is so difficult to provide in leather footwear. Such shaping of the quarters 25 and 26 secures a snug fit which keeps the foot from sliding up and down within the counter and assures maximum comfort. Since the plastic material is flexible and elastic, the counter 17 is automatically adaptable in shape to the particular shape of any certain person's heel of normal contour and is not subject to the misshaping characteristic of leather shoes which may result from dampening by perspiration or water and then drying to a distorted set.

The forepart tread sole portion 18 and the shank por-

tion 19 connecting it to the heel breast 22 preferably are of conventional shape to assure maximum comfort to a person's foot with the particular height of heel 16 employed in the embodiment illustrated by way of example. If desired the shank portion 19 may be strengthened by any suitable insert which may be interposed thereon beneath an insole or molded into the shank portion to give better support to a person's arch.

The vamp foxing 20 comprises an upstanding wall extending upwardly, preferably continuously, along the margins of the forepart tread portion 18 and the shank portion 19 to an appreciable height to form the vamp side walls, and preferably to a height less than the thickness of the forepart of an average person's normal foot, e. g., the ball of his foot and toes. Vamp foxing 20 merges with the concaved quarters 25 and 26 to form forward extensions thereof. The upper edge 27 of the vamp foxing 20 curves upwardly to smooth emergence with the upper edge 28 of the counter portion 17, as shown in the drawing. It will thus be seen that the portions of the top edge of the continuous upstanding wall provided by the counter 17 and vamp foxing 20 which extend across each of quarters 25 and 26 and along the shank portion 19 to the portions of the foxing along the tread sole portion 18 are of smooth, relatively flat ogee shape.

As proposed in Fig. 3, the heel well 24 is filled with a body 29 of suitable filler material, such as cork, soft or sponge rubber, or other light-weight resilient or elastic substance, so as to minimize the shock to a person's body when the heel strikes the ground during striding. It has been found that such a filled heel transmits much less shock to a person's body than does a solid heel, even when the latter is provided with elastic lifts. Preferably, the basic unit 10 is provided with a suitable insole 30, the back portion of which overlays and covers the filler body 29; and, if desired, the tread and shank portions 18 and 19 are shaped externally to simulate the edges of an outsole. The elasticity of the molded unit permits ready stripping from the mold cavity even though there be undercut areas.

The basic shoe unit 10 may be employed in the construction of a vast variety of styles of footwear since uppers of various types may be readily attached to and mounted thereon. For example, as illustrated in Fig. 4, such basic shoe unit 10 of the illustrated shape may be readily converted into a sport oxford by perforating the upper margins of the vamp foxing 20 and fastening thereto by laces, such as is illustrated in dotted lines at 31, an attractive forepart or vamp upper 32, illustrated in dot-dash lines. From a stock of such molded plastic basic units 10 one can create and produce literally hundreds of different styles of shoes. A particular model of basic unit 10 in both rights and lefts may be stocked by a manufacturer in some fifty-six different variations in sizes and widths, which will selectively fit the feet of average people and, of course, different models of such basic units may be stocked in such variations to multiply the number of possible styles, such as those of a sport line, those for street wear, pumps, sandals, etc. To such basic units may be attached in simple manner a variety of types of cross straps, perforate and imperforate vamp uppers and toeless foreparts, as well as oxford upper portions, uppers for high-cut boots, opera pumps, etc., and by any suitable decorative means, such as lacings, eyelets, stitching and the like. Such molded plastic basic shoe units, of course, may also be produced for women's, men's and children's footwear as well as for orthopedic and corrective shoes and even for employment in the construction of medical prescription shoes where fit must be exact with respect to ill-shaped and deformed feet. Such standard lines of shoes and such special footwear may be produced with the employment of basic shoe units of the present invention at a cost much cheaper than that required by shoe manufacturers of similar footwear from leather and

other materials standard in the art as employed in accordance with standard practices. Despite such economy permitting such shoes to be marketed at much cheaper retail prices, the resultant shoes have many advantages over leather footwear in that the molding thereof provides an unusually attractive finish without requiring tedious and costly finishing operations while assuring that the resulting footwear will be waterproof with respect to wet surfaces over which one strides, without necessarily preventing free air circulation since suitable provision therefor may be made in the uppers attached thereto. Footwear made with the employment of basic units of the present invention also is sturdy and may be substantially scuff-proof by the employment of suitable tough plastic material as well as long-lived to outwear similar models made from leather. Also, by being waterproof, such shoe bottoms also assure elimination of accident hazards since the plastic material may be electrically non-conductive and the soles thereof may be of a non-slip quality, minimizing the hazard of falling. Such basic shoe units also assure against destruction by mold and bacteria, which is of particular concern in damp climates and tropical countries.

It will thus be seen that the objects set forth above, among those made apparent from the preceding description, are efficiently attained and, since certain changes may be made in the above article without departing from the scope of the invention, it is intended that all matter contained in the above description or shown in the accompanying drawing shall be interpreted as illustrative and not in a limiting sense.

It is also to be understood that the following claim is intended to cover all of the generic and specific features of the invention herein described, and all statements of the scope of the invention which, as a matter of language, might be said to fall therebetween.

Having described my invention, what I claim as new and desire to secure by Letters Patent is:

A molded plastic, basic shoe unit comprising integral shoebottom portions of waterproof, flexible and elastic plastic material of good wearing quality and sufficient stiffness to tend to retain its shape in use; the integral portions comprising, in combination; a relatively flat, shaped forepart tread sole portion; a shaped, arched shank portion extending rearwardly and upwardly from the back of said tread sole portion and merging smoothly therewith; a relatively low, hollow heel portion integrally connected to the back end of said shank portion and having a relatively wide, substantially flat bottom of D-shaped outline, a transverse, relatively low breast extending upwardly from and integral with the front edge of said heel bottom, and relatively low sidewalls extending upwardly from and integral with the remaining marginal edges of said heel bottom with said sidewalls being smoothly curved about the rear side of said heel portion, said heel bottom, heel breast and heel sidewalls together defining an open top well; an upwardly-extending full counter superposed above the heel sidewalls and constituting two integral, complementary, full quarters with each of the latter concaved appreciably inwardly on its side face for snug fit to the inner and outer sides of a person's heel; and a vamp foxing consisting of a continuous wall upstanding from and integral with the marginal edges of said tread sole and shank portions; the height of said foxing wall along the edges of said tread sole portion being appreciably less than the thickness of an average person's normal foot with the top edge of said foxing along the edges of said forepart tread sole portion being at approximately the same elevation at all points, the top edge of said foxing along the edges of said shank portion curving gradually upwardly back toward the top edges of said quarters to smooth emergence therewith with gradual progressive increase of the height of said foxing wall along said shank portion, said counter and said foxing wall together providing a continuous upstanding wall along said tread sole, shank and heel portions

with the top edge thereof across each quarter and along the shank portion to the foxing along the tread sole portion being of smooth, relatively flat ogee shape, said foxing wall being adapted to have attached thereto vamp upper means to provide a full shoe; said shoe unit having a separate body of relatively light-weight, shock-absorbing filler material substantially filling the heel well, and an insole overlying the upper surface of said tread sole and shank portions and said body of filler material.
